UNITED STATES PATENT OFFICE

CHARLES W. LE FEBVRE, OF CHICAGO, ILLINOIS

WINDOW AND THE LIKE

Application filed August 29, 1930. Serial No. 478,755.

This invention has to do with certain improvements in windows and the like. The features of the invention are particularly applicable to the construction and operation of 5 windows of that type in which the sash are mounted for vertical movement in the casing.

The main object of the invention is to provide a window construction which is so arranged that the sash thereof can be swung or turned out into the room in order to make them accessible for cleaning or similar operations. In this connection, it is particularly an object to provide an arrangement such that both the upper and lower sash can be thus turned or swung out into the room when in the lowered position, in which position they are most easily accessible for cleaning and similar operations. In this connection 20 it is noted that it is customary to place the upper sash at the outside face of the lower sash so that during the raising and lowering operations the upper sash passes or occupies a position at the outside face of the lower sash. Furthermore, it is customary to provide for a certain amount of lap, or overlying face to face engagement of the top rail of the lower sash and the bottom rail of the top sash when the sash are in their normal 25 closed position. This overlap insures such an engagement between the adjoining sash as to insure a weather tight or air tight contact between the parts.

It will be noted, in connection with the 30 foregoing circumstance, that upon raising the lower sash to the raised position as ordinarily established heretofore, the lower edge of said sash does not rise high enough to allow the upper edge of the upper sash to pass beneath it when the upper sash is fully lowered. In other words, according to previous constructions the two sash will interfere to such an extent that it is not possible to swing the upper sash inwardly by a simple pivoting 35 or hinging operation.

One of the features of the present invention relates to the provision of a construction in which there is provided an extra amount of head room or space above and in line with the lower sash so that when said sash is raised

it may be moved up an extra distance into said head room so as to raise its lower edge high enough to permit the top edge of the upper sash to swing beneath it when the upper sash is moved to its lowermost position. 55

Another feature of the invention relates to the provision of a very simple and strong construction for supporting both of the sash and permitting them to slide readily, while at 60 the same time establishing the necessary hinging relationship.

Another feature of the invention relates to the provision of an improved construction of stop strip, which can be readily slid up 65 out of the way in order to permit the sash to be swung out into the room under the proper conditions.

Another feature of the invention relates to the provision of an improved construction of parting strip which can be readily removed in order to allow the upper sash to be swung out into the room when it is lowered to the proper position. 70

Another feature of the invention relates to the provision of an improved construction embodying the slide and the hinge connection for the sash, said slide being so arranged as to also make proper provision for connection of the counter balance weight thereto. 75

Other objects and uses of the invention will appear from a detailed description of the same, which consists in the features of construction and combinations of parts herein-after described and claimed. 80

In the drawings:

Figure 1 shows a face view of a window casing, together with upper and lower sash therefor, all of said parts embodying the features of the present invention; 85

Figure 2 shows a cross section on the line 2—2 of Figure 1, looking in the direction of the arrows, and it shows by dotted lines the manner in which the two sash can be swung out into the room; 90

Figure 3 shows a section on the line 3—3 of Figure 1, looking in the direction of the arrows, the same having reference to the upper sash;

Figure 4 shows a section on the line 4—4 100

of Figure 1, looking in the direction of the arrows, the same having reference to the lower sash;

5 Figure 5 shows a vertical section on the line 5—5 of Figure 1, looking in the direction of the arrows, and it shows the additional head room provided for the lower sash, the lower sash being shown in lowered position by full lines and in raised position by means of dotted lines;

10 Figure 6 shows an edge view looking at the right-hand edge of Figure 1;

Figure 7 shows an edge view looking at the left hand edge of Figure 1;

15 Figure 8 shows a fragmentary section on the line 8—8 of Figure 1, looking in the direction of the arrows; and

20 Figure 9 shows a fragmentary view similar to that of Figure 3, but illustrating a modified type of construction of the slide.

In the different views Figures 3, 4, 8, and 9, are on enlarged scale as compared to the remaining figures.

25 The construction illustrated includes a casing having the side portions 10 and 11, the head 12, and the sill portion 13. The construction also includes the upper and lower sash 14 and 15 respectively. For purposes of convenience the sash as well as the casing are shown as being made principally of wood construction although manifestly sheet metal or other suitable constructions might be used.

30 As shown especially in Figure 5, the lower rail 16 of the upper sash 14 and the upper rail 17 of the lower sash 15 overlap when the sash are in the closed window position, which is illustrated in Figure 5. As one feature of my invention, I provide a slotted opening 18 in the head portion 12 and above and in line with the lower sash 15 so that said lower sash can be raised an extra distance as shown by the dotted lines in Figure 5. Preferably a false cap or head 19 is placed over the slotted opening 18 but sufficiently elevated to permit the necessary freedom of movement of the lower sash into the full dotted line position. This movement is sufficient to permit the sash 14 to swing beneath the fully raised lower sash as will be evident from inspection of Figure 5. In that figure, the dotted line 20 indicates the bottom edge of the fully raised lower sash and the dotted line 21 indicates the top edge of the fully lowered upper sash 14 and comparison indicates that the sash can pass as already explained.

35 Examination of Figures 2 and 4 shows that there is provided a slide plate 22 for the lower sash. This slide plate passes through a slotted opening 23 in one side of the window casing, which slotted opening may be extended the full height of the casing if desired. The inner edge 24 of this slide plate is hooked as shown in Figure 4 and is thus 40 adapted to engage the tongue portion of an

angle-bar 25 which extends vertically inside of the casing and is secured to the casing in suitable manner as by means of the screws indicated in Figure 4.

45 The edge portion of the slide 22 slightly overlies the edge of the lower sash 15 to which it is hingedly connected as shown at 26. The result is that the lower sash can be turned out into the room as shown by the dotted line position of Figure 4. Preferably an angle bar 27 is secured to the slide adjacent to the face of the casing as shown in Figure 4, so as to assist in guiding the parts during their sliding movement and also to make the construction more air-tight.

50 The strip 28 is secured to the face of the casing in front of the hinged edge of the lower sash 15. As clearly shown in Figure 4 in particular, the face 29 of the strip 28 is cut back or relieved so as to provide the necessary clearance to allow the upper sash to swing out into the room as will be presently explained.

55 Due to the fact that the slide plate 22 extends for substantially the full height or vertical dimension of the lower sash, a very strong support is provided for the lower sash so as to take care of the severe tendency to rock or rotate the slide 22 about a horizontal axis extending at right angles to said slide.

60 There is also provided a slide plate 30 for the upper sash 14, said plate 30 extending through a slotted opening 31 in the other side of the casing; and the inner edge 32 of the slide plate 30 is bent or hooked over to engage an angle bracket 33 secured to the inside portion of the casing in manner similar to that already explained with respect to the lower sash. Likewise, the slide 65 plate 30 extends through the casing and slightly overlies the edge of the upper sash 14 to which it is hingedly connected by the hinge connection 34.

65 Strips 35 and 36 are permanently secured to the sides of the casing in position to guide the outside face edges of the upper sash 14.

70 The other edge of the lower sash 15 is guided by a specially constructed strip, the details of which are best shown in Figures 3, 5, and 8. This strip includes a slidable section 37 of vertical dimension somewhat greater than that of the lower sash. Said strip 37 is provided with angle strips 38 and 39, secured to its inside edge corners. The central portion of the back face of the strip 37 is cut away or recessed vertically to receive a plate 40. Said plate is secured to the face of the casing by means for screws and in proper spaced relationship by means of a spacer strip 41. The result is that the angle plates 38 and 39 hook behind and engage the plate 40 which thus guides the strip 37 in its vertical movements.

75 The strip 40 extends the full height of the

casing. Consequently, it is possible to slide the strip 37 up high enough to carry its lower edge high enough to permit the lower sash to be swung out into the room without 5 interference from said strip.

Preferably a channel-shaped box strip 42 is secured to the face of the casing above the position of the lower sash so that the strip 37 will run up into said strip 42 and 10 thus permit the two parts to be telescoped together. This will establish a finished appearance for the structure and at the same time assist in guiding the sliding movements of the strip 37.

15 There is a parting strip 43 permanently secured to the casing between the edges of the upper and lower sash at the hinged edge of the upper sash as shown in Figure 3. There is a removable parting strip 44 between 20 the upper and lower sash at the position of the swinging edge of the upper sash 14 (see Figure 4). This removable parting strip 44 is carried by a plate 45 which can be slid back beneath another plate 46 which has 25 its upper and lower edges permanently connected to the casing. Upon swinging the lower sash out into the room or upon raising the lower sash to the full extent, this parting strip 44 can be slid or pulled out into 30 the room as will be clearly evident from examination of Figure 4.

It will be evident from the dotted line 47 in Figure 4 that the swinging edge of the 35 upper sash can pass the strip 28 by reason of the fact that the face 29 of said strip is cut back or relieved as shown in Figure 4.

Each of the slides 22 and 30 is provided 40 with a bracket 48 in which there is connected a cord 49 passing up over a pulley 50 in the upper portion of the casing and carrying a counter-weight 51 at its lower end, all of 45 which is best illustrated in Figures 6 and 7.

In the modified construction of Figure 9, 50 the slide plate 52 is shown of angle form instead of straight as in Figures 3 and 4 in particular. When using this angle form the slot 53 in the casing may be offset from the position of the hinge 54. Also, when this construction is used it is possible to provide a weather 55 strip 55 which extends forwardly from a position beneath the casing strip 56 to overlie the central angular portion of the slide, occupying a position between said angular portion and the edge of the sash. This will materially 55 improve the weather resisting qualities of the structure.

While I have herein shown and described 60 only certain improvements of the features of my present invention, still I do not intend to limit myself thereto except as I may do so in the claims.

I claim:

1. In a window construction, the combination 35 of a casing, upper and lower sash therefor, and means for individually supporting

said sash to permit them to slide freely up and down independently of each other, together with removable parting and guide strips located at opposite sides of the casing, said removable parting strip including a parting 70 member, together with a relatively thin plate to which said parting member is connected, said plate normally lying in face contact with the face of one side of the casing and between the casing and the edge of the upper sash, and 75 the slidable parting strip including telescoping members, the larger of which is permanently secured to the upper portion of the side of the casing, and the lower of which is slidably connected to said side of the casing and 80 in position to telescope upwardly into the first mentioned section, substantially as described.

2. In a window construction, the combination 85 of a casing, upper and lower sash slidably mounted therein, and guide strips for said sash, at least one of said guide strips being movable from a working position to a non-working position, said guide strip including upper and lower telescoping sections, the 90 upper section comprising a channel shaped sheet metal strip having one edge secured to the casing, said channel strip being located at the non-working position, and also including an inner section slidably connected to the face 95 of the casing in line with said channel strip and in telescoping engagement with the channel strip to slide up into the channel strip for the non-working position, substantially as described. 100
